UNITED STATES PATENT OFFICE.

BERNARD A. ENGHOLM, OF SEATTLE, WASHINGTON, ASSIGNOR TO THE ROLA COMPANY, OF SEATTLE, WASHINGTON, A CORPORATION OF WASHINGTON.

LOUD-SPEAKING TELEPHONE RECEIVER.

Application filed January 5, 1925. Serial No. 545.

My invention relates to magnetic structures, and to electromagnetic devices formed therewith, more especially designed for use in loud speaking telephone receivers such as 5 are employed in radio communication.

Among the important objects of my invention are, first, the provision of a highly sensitive electromagnetic structure wherein hysteresis and like losses are reduced to the 10 minimum; the provision of a general arrangement of such structures which is cheap and convenient for assembly and for association with other parts to complete the telephone receiver; and in which the several 15 parts lend themselves readily to precision machine manufacture, hence can be most accurately made and assembled; the provision of such a structure wherein the several parts are so associated and held in position 20 that they are not liable to damage from handling; the provision of a structure in which the necessity for adjustments is reduced to a minimum but wherein such adjustment as is essential may be readily 25 made, and in general, the simplification and improvement of such magnetic and electromagnetic devices as are intended for the purpose mentioned, both of themselves and within the unit.

30 My invention is comprised in the novel magnetic structures and the novel association therewith and therein of electromagnetic devices, as shown in the accompanying drawings, described in the specification and 35 more particularly defined by the claims terminating the same.

In the accompanying drawings I have illustrated an embodiment of my invention which is its present preferred form.

40 Figure 1 is an axial sectional view through the assembled device on the line 1—1 of Figure 2, and Figure 2 is a bottom plan view thereof, the binding posts and support therefor being omitted.

45 Figure 3 is an exploded view in perspective, and Figure 4 is an assembly view, likewise in perspective, of the pole tip unit and associated parts.

Figure 5 is an enlarged vertical section through the pole tip unit and associated 50 parts, substantially on the line 5—5 of Figure 6, and Figure 6 is a horizontal sectional view through the same unit on the line 6—6 of Figure 5.

Figure 7 is a detail in perspective showing the manner of assembling the armature.

In previous devices designed for employment in loud speaking telephone receivers it has been found that the electromagnetic structure was more or less delicate and required exceedingly careful handling to prevent its being thrown out of adjustment or otherwise damaged. Another difficulty in previous devices has been the impossibility, with the construction employed, of making the several parts sufficiently accurate to enable them to fit together perfectly and without adjustment. Where attempts have been made to overcome the latter difficulty, by providing for adjustment of all parts, the 70 first difficulty has been increased, the large number of adjustments rendering the device delicate, but the lack of precision inherent in the necessary mode of constructing the several parts necessitating a large number 75 of adjustments. These compensate well enough for this lack of accuracy which is a necessary evil when employing machined parts, but such adjustments are liable to be improperly made through carelessness, or 80 the parts are liable to be thrown out of adjustment. Such devices are also difficult to adjust and to assemble.

85 My device is intended to be built up of units which can be formed by precision machines, as by dies, so that the several parts can be many times more accurately formed and assembled than is possible by forging and finishing similar parts of the same material. By accurately forming the parts 90 their assembly is simplified, and the necessity of adjustment is eliminated. In my device there is, in fact, only a single adjustment, to the armature support, and while this also might be eliminated, I prefer to 95 retain it to permit variation of the tone of

the reproducer. The device is assembled in complete separable units, in which all parts are held in definite relationship to each other and in such manner that handling or accidental jarring, and in fact, rather rough usage, will not harm the structure. It also simplifies the assembly of the entire device and its connection to the sound reproducing portion of the telephone receiver.

10 As a basis for the entire device I employ a permanent magnet 9 which may be formed nearly circular. Preferably its opposing ends are separated somewhat. This magnet is suitably supported in association with 15 sound reproducing devices such as the diaphragm 8, the diaphragm being supported between the usual resilient rings 80 in a cap 81, the cap being secured upon a casing 82 and a horn 83 being supported upon the 20 cap. It will be understood that these details of the sound reproducing device form no essential part of this invention and may be replaced by any that are found suitable.

Between the ends of the magnet 9 and 25 preferably toward the center of the ring-shaped magnet I position a pole tip unit, best illustrated in Figures 3, 4, 5 and 6. This unit includes two opposing pole tips 1, spacer means such as the non-magnetic bars 2, an 30 armature 3 supported from the spacer bars and having its ends positioned between the pole tips, a coil or coils 4 held within the unit and operatively positioned relative to the pole tips 1, and means such as the 35 through bolts 5 for maintaining all of these elements in the pole tip unit in definite spaced relation, except as will be apparent hereafter.

This pole tip unit, the separate elements 40 of which will be more particularly described hereafter, is held in position between pieces which are essentially clamping devices, but which serve as magnetic conductors between each end of the magnet 9, and the corresponding pole tips 1. These pole pieces 90 are each secured by one end to the opposing ends of the magnet 9, as by means of the bolts or screws 92, and their other ends overlap. Between these overlapping ends of the 50 pole pieces 90 the pole tip unit is positioned, and by means of clamping screws 91 passing through apertured lugs 93 in one pole piece and received in like lugs of the other pole piece, the pole piece may be drawn down and clamped upon the adjacent pole tips forming part of the pole tip unit to establish 55 good magnetic contact therewith. Also by properly positioning the lugs 93 of the pole pieces, as may be done accurately by punching out these pieces, the clamping screws 91 may be made to lie in contact with the side faces of the pole tip unit, as is best shown in Figures 5 and 6, and thus to hold this unit against displacement relative to the pole

pieces. If, as shown herein, the screws 91 65 engage the pole tips 1, the screws 91 must be of non-magnetic material.

Because of the clamping action of the pole pieces 90 upon the pole tips 1, and also because of the desirability of preventing accidental displacement of the pole tips relative to each other and relative to the armature 3, it is essential that they be held in definitely spaced relation. It is also desirable to eliminate hysteresis losses and the 75 like, thus increasing the sensitivity and faithfulness of reproduction of the device. Again, accuracy of the pole tips as a whole, and accuracy of the spacing between the opposing tips, can best be secured by punching 80 them out of the high silicon steel which is most desirable for this use. For these reasons the pole tips are laminated. The several laminations in each pole tip may be secured together and both pole tips may be 85 held in definitely spaced relation by punching in the laminations of each pole tip and to receive the through bolts 5. Preferably the pole tips are bifurcated or U-shaped so 90 that the two legs of each pole tip are positioned opposite like legs of the other pole tip, and the holes 15 and bolts 5 passing through form a means for accurately alining and registering the legs 11 of the pole tips. The through bolts 5 are also secured and 95 supported in the spacer bars 2, of which two may be employed, the two being shown herein as lying at opposite sides of the pole tips. Suitable nuts 51 thread upon the bolts 5 at each end, by means of which the spacer 100 bars and the laminations of the pole tips may be drawn together into a single unit and held immovable.

The armature is of special construction. It is desirable to provide an armature of sufficient mass and so formed that it will not become saturated but will at all times remain sensitive, yet it is desirable so to support this armature that it will be immediately responsive to electromagnetic impulses. 105 Also, for the same reasons that the pole tips 1 are laminated, it is desirable to laminate the armature 3. Laminating the armature produces another advantage, in that the magnetic flux will enter the several laminations more readily from their edges, and the reluctance of the armature is thus reduced, and its saturation point is raised. This may be assisted by punching the laminations 110 lengthwise of the grain of the metal. 120

For the support of the armature I have shown a resilient strip 31 which may be suitably supported from the spacer bars 2, as, for example, by studs 32 receivable in a hole 125 23 in the spacer bars. Essentially the studs 32 form part of the armature support and may be connected to the ends of the resilient strip 31 by passing a small key or pin 30

through registering holes provided in the end of the stud 32 and strip 31, the end of the stud 32 being shown as split to receive the end of the strip 31. By threading the outer ends of the studs 32 where they protrude beyond the spacer bars 2, and by providing an adjusting nut 33 therefor, it is possible also to adjust slightly the angle of the armature 3 about the axis of the studs 32, 10 and to hold it in adjusted position. It is possible also to adjust the tension in the strip 31, to vary its resistance to movement, and to change the natural period of the armature, and thereby the tone of the reproducer. 15 By twisting one stud in the opposite direction to the other the strip 31 is greatly stiffened, its initial tension being greatly increased. Set screws 39 hold the studs in adjusted position.

20 The several laminations of the armature 3 may be supported in the strip 31 in any suitable manner so that they are retained in proper position relative to each other. As a convenient means of securing this result I have formed the laminations with a shouldered lug or lugs 34 substantially at their centers and have provided in the strip 31 a longitudinally extending slot 35 through which the ends of the laminations may be 30 passed until the shoulders of the lugs 34 engage the strip 31. The shoulders then serve as stops for the individual laminations. Preferably these laminations are inserted first from one side of the strip 31 and next 35 from the other side, alternating so that lugs of adjacent laminations lie upon opposite sides of the strip 31. This leaves interstices between lugs and by applying a small amount of solder substantially at the center of movement of the armature, the several laminations after complete assembly may be held together and held in fixed relationship to the supporting strip 31, yet without increasing to any appreciable degree the movable mass 40 of the armature and without unbalancing it to any appreciable extent. Two of the laminations, at about the center of the series, may be slightly prolonged, as indicated at 36, and to these prolongations may be secured in any 45 suitable manner, as by a drop of solder, the connecting link 84 extending to the diaphragm 8.

It is desirable to space the ends of the legs 11 of opposing pole tips as little as possible, 55 for the magnetic reluctance of the air gap varies as the square of the distance between poles. It is not desirable, however, to cut down the distance through which the end of the armature, interposed between these 60 spaced pole tips, may oscillate. By chamfering the ends of the armature, as is indicated at 37, the armature is given an increased distance through which it may move without coming into contact with the pole tips, yet

without decreasing the distance between the pole tips and the nearest point of the armature, at the inner edge of each leg 11. As the armature approaches the limit of its movement its chamfered end becomes nearly parallel to the end plane of the pole tip, instead of presenting a corner which would contact with the pole tip. By thus permitting unrestricted movement of the armature the faithfulness of its reproduction is increased. This effect may also be assisted by reason of the fact that the increase in resistance of the torsional mounting, towards the limits of the armature's movement, is compensated for by the increase in flux through the armature due to the increase in area of surface through which the flux passes readily. 70 The coil 4 is included within the pole tip unit. For this purpose I have found it desirable to form the spacer bars 2 in the form of channels, the webs of these channels being spaced outward from the pole tips 1 and their flanges 21 being alined with the legs 11 of the pole tips and bearing against the outside laminations of each of the two opposing pole tips. In this manner the channeled spacer bars 2 and the U-shaped pole tips form a housing within which the coil 4 is received. This form lends itself readily to precision manufacture, the length of the spacers being determined by definitely spaced tools, and the necessary holes being drilled in it by a gang drill while the channel is held in definitely positioned jigs. 80

90 Preferably the coil is divided into two parts, these two parts being held slightly spaced. For this purpose the inner ends of the studs 32, which project slightly through the web of the channeled spacer bars 2, are shouldered to provide a reduced portion 38. The two parts of the coil 4 then are each held between the inner faces of the flanges 21 of the spacer bars and the inner faces of the legs 11 of the pole tips on the one side, and the reduced portions 38 of the two studs 32 on the other side. They are also formed of a size so that they fit exactly between the bottoms of the U-shaped pole tips 1, and they are provided with central apertures 41 through which the ends of the armature 3 extend. It will be understood that the coils are wound upon nonmagnetic spools 40, as bakelite. Thus the two coils are definitely held against movement within the housing formed by the two pole tips 1 and the two opposite spacer bars 2 and surrounding the ends of the armature 3 and in such association with the pole tips 1 as to give the maximum effect to fluctuations of the electric impulses in producing movement of the armature. 100

110 The device as thus constituted comprises a pole tip unit consisting of the spacer bars 2 holding between them and in definitely

spaced relation the laminated pole tips 1, these pole tips and spacer bars forming a housing within which the two coils 4 are held in definite relationship, substantially immovable, and the spacer bars forming a support whereby the armature 3 may be held in definite relation to the pole tips and substantially enclosed within the pole tip unit so that it is not liable to be damaged. If adjustment of the position of the armature is necessary this may be accomplished by varying slightly the angular position of the studs 32, and if adjustment of the tension of the strip 31 and consequently the degree of movement of the armature 3 is found desirable this may be done by separating the studs 32 or allowing them to approach by means of adjustment of the nuts 33. Torsional adjustment of one stud against the other stiffens the mounting, as has been noted. Outside of adjustment, which is intended for the convenience of the assembler and tester, it has been found that no further adjustment is desirable or necessary, parts being accurately formed. For greater security in maintaining any adjustment of the armature mounting, I may provide the set screws 39, engaging the studs 32, as mentioned heretofore.

This pole tip unit may be readily handled, and to assemble it into the telephone receiver it is only necessary to clamp it between the pole pieces 90 by means of the clamping screws 91. In this connection it should be noted that the spacers 2 do not space apart the pole pieces 90, except indirectly. They are secured directly to the pole tips 1, which extend slightly above and below the ends of the spacer bars 2, so that the latter do not contact with either pole piece 90. If after securing the unit between the pole pieces 90 adjustment of the position of the pole tip unit relative to the connecting link 84 is necessary, this may be accomplished prior to final tightening of the clamping screws 91 by adjustment of the pole pieces 90 relative to the securing bolts 92. These bolts 92 may also serve to support a non-magnetic base 6 upon which binding posts, indicated at 61, may be supported, these being electrically connected, as is well understood, to the terminals of the coils 4 and to the lead-in wires (not shown). There remains only the connection of the connecting link 84 to the protruding tip 36 of the armature, which may be accomplished by means of a drop of solder or any other suitable means. Thus connected the armature and its support is under no tension whatsoever, but is free to be moved in opposition to the torsional resistance of the resilient strip 31 upon passage of suitable electrical impulses through the coils 4.

What I claim as my invention is:

1. A magnetic structure comprising a

magnet having its opposing poles disposed in overlapping relation, two pole tips therebetween, means maintaining said pole tips in definitely spaced relation, and means for clamping said pole tips between the overlapped poles. 70

2. A magnetic structure comprising a magnet having its opposing poles disposed in overlapping relation, two pole tips therebetween, means rigidly maintaining said pole tips in spaced relation, and means for drawing each magnet pole into intimate contact with its respective pole tip. 75

3. A magnetic structure comprising a magnet, a magnet pole tip unit comprising two opposed pole tips and spacer means secured to each of said pole tips to maintain a definite spaced relation therebetween, two pole pieces having overlapping ends, their other ends being secured to respectively opposite poles of the magnet, and their overlapping ends each contacting with one of said pole tips, and means for clamping said pole tip unit between the overlapping ends of said pole pieces. 80

4. A magnetic structure comprising a magnet, a magnet pole tip unit comprising two opposed pole tips and spacer means secured to each of said pole tips to maintain a definite spaced relation therebetween, two pole pieces having overlapping ends, their other ends being secured to respectively opposite poles of the magnet, and their overlapping ends each contacting with one of said pole tips, and means for clamping said pole tip unit between the overlapping ends of said pole pieces, said clamping means comprising a plurality of screws extending through one pole piece and threading into the other, and disposed at opposite sides of and engaging said pole tip unit to maintain it in definite relationship to said pole pieces. 95

5. A magnet pole structure comprising a pair of opposed pole tips, channel-like non-magnetic spacer bars at opposite sides of said pole tips, said spacer bars being secured directly to each pole tip to maintain the tips in definitely spaced relation and to form therewith a housing. 100

6. A magnet structure comprising a pair of opposed laminated pole tips, non-magnetic spacer bars at opposite sides of the series of laminations and extending between opposite pole tips to maintain them in definite spaced relation, said bars being recessed between their sides and ends to form a housing, in conjunction with the pole tips, means for maintaining registry of the laminations in each pole tip, and means for securing the spacer members and the laminations of each pole tip together to form a unitary structure. 115

7. A magnet pole structure comprising a pair of opposed bifurcated pole tips, non-magnetic spacer means disposed at opposite 120

5 sides of the two pole tips, said spacers in the extension of the space between the legs of the pole tips, being recessed to form a housing in conjunction with said pole tips, and means for clamping the pole tips between said spacers to form a unitary structure.

8. A magnet pole structure comprising a pair of laminated pole tips each having registering holes in the several laminations thereof, a non-magnetic spacer bar extending between the two pole tips at opposite sides thereof, said bars being recessed between their sides and ends to form a housing, in conjunction with the pole tips, a clamping bolt extending between said spacer members and through the holes in the laminations of the pole tips to maintain said pole tips in definite spaced relation, and 10 clamping nuts threaded upon said bolts for clamping said spacer members and the several laminations of the pole tips into a unitary structure.

9. An armature mounting for an electro-25 magnetic structure comprising a pair of spaced supports, a stud receivable in each support, a resilient strip extending between said studs, an armature supported in said strip, and means for adjusting the relative 30 positions of said studs.

10. An armature for an electromagnetic structure comprising a pair of spaced supports, a slotted strip extending between said supports, and a plurality of laminations ex-35 tending through said slot in the strip.

11. An armature for an electromagnetic structure comprising a plurality of laminations, an armature support, and positioning 40 means engageable between the support and each lamination to maintain the several laminations fixed in relationship.

12. An armature for an electromagnetic structure comprising a plurality of laminations each having a shoulder substantially 45 at its center, and a slotted supporting strip therefor, each lamination being inserted through the slot in said strip to contact its shoulder with the strip, and adjacent laminations being inserted from opposite sides 50 of the strip.

13. An armature for an electromagnetic structure comprising a resilient strip and a plurality of laminations supported therefrom, for oscillatory movement about the 55 axis of said strip.

14. An armature for an electromagnetic structure comprising a resilient strip and a plurality of laminations supported therefrom, a support for each end of said strip, and means for varying the tension in said 60 strip.

15. An armature for an electromagnetic structure comprising a slotted supporting strip, a plurality of laminations each having 65 shouldered lugs substantially at its center,

each lamination being inserted endwise through the slot in said strip to contact the shoulders of said lugs with the strip, adjacent laminations being inserted from opposite sides of the strip, and the interstices 70 between lugs being filled with solder to unite the laminations and the supporting strip.

16. An electromagnetic structure includ-75 ing a pair of opposed pole tips, non-magnetic spacer means at opposite sides of said pole tips and secured to each pole tip to maintain them in definite spaced relation, an armature positioned between said pole tips, and a resilient strip supporting said armature, the ends of said strip being supported 80 in opposite spacers.

17. An electromagnetic structure includ-85 ing a pair of opposed pole tips, non-magnetic spacer means at opposite sides of said pole tips and secured to each pole tip to maintain them in definite spaced relation, an armature, including a transverse resilient supporting strip, positioned between said pole tips, and means secured in opposite spacers and engaging opposite ends of said 90 resilient strip to support the armature.

18. An electromagnetic structure includ-95 ing a pair of opposed pole tips, non-magnetic spacer means at opposite sides of said pole tips and secured to each pole tip to maintain them in definite spaced relation, an armature, including a transverse resilient supporting strip, positioned between said pole tips, means secured in opposite spacers 100 and engaging opposite ends of said resilient strip to support the armature, and means for adjusting the angular position of and tension in said strip.

19. An electromagnetic structure comprising 105 a pair of bifurcated pole tips each having its two legs positioned opposite like legs of the other pole tip, two channeled non-magnetic spacer bars having the edges of their channels alined and contacting with the legs of the pole tips to form a housing, means connecting said channels and pole tips together to maintain the pole tips in definitely spaced relation, an armature having its ends positioned between the legs of said pole tips and supported between its ends from said spacer bars, and coils within the housing formed by said spacer bars and pole tips and operatively positioned relative to said armature.

20. An electromagnetic structure comprising 110 a pair of bifurcated pole tips each having its two legs positioned opposite like legs of the other pole tip, two channeled non-magnetic spacer bars having the edges of their channels alined and contacting with the legs of the pole tips to form a housing, means connecting said channels and pole tips together to maintain the pole tips in definitely spaced relation, an armature having its ends 115 positioned between the legs of said pole tips 120

and supported between its ends from said spacer bars, a pair of coils within the housing formed by said spacer bars and pole tips, and each surrounding an end of said armature.

21. An electromagnetic structure comprising a pair of bifurcated pole tips each having its two legs positioned opposite like legs of the other pole tip, two channeled non-magnetic spacer bars having the edges of their channels alined and contacting with the legs of the pole tips to form a housing, means connecting said channels and pole tips together to maintain the pole tips in definitely spaced relation, an armature having its ends positioned between the legs of said pole tips and supported between its ends from said spacer bars, a pair of coils within the housing formed by said spacer bars and pole tips, and each surrounding an end of said armature, and means engaging said coils to maintain them fixed in position.

22. An electromagnetic structure comprising a pair of bifurcated pole tips each having its two legs disposed opposite and adjacent to like legs of the other pole tip, two non-magnetic spacer bars extending between said pole tips at opposite sides thereof, to form therewith a housing, means connecting said spacer bars and said pole tips to maintain the latter in definitely spaced relation, an armature positioned between said pole tips, armature supporting means extending between said spacer bars, and including a shouldered stud supported in each of said spacer bars, and a coil within said housing at each side of said shouldered studs and operatively positioned relative to said armature, each coil being held between the adjacent legs of both pole tips and the reduced portions of said two shouldered studs.

23. An electromagnetic structure comprising a pair of U-shaped pole tips each having its two legs disposed opposite and adjacent to like legs of the other pole tip, two channeled non-magnetic spacer bars having the edges of their channels alined and contacting with the legs of the pole tips to form a housing, means connecting said spacers and pole tips to maintain the latter in definitely spaced relation, an armature having its ends disposed between adjacent legs of the two pole tips, armature supporting means extending between the webs of the channeled spacers and including a shouldered stud received in each spacer, and a coil surrounding each end of the armature within said housing, and maintained definitely fixed in position therein by contact with the bottoms of both U-shaped pole-tips, with the inside of the legs, and with the reduced portions of the armature-supporting studs.

24. An electromagnetic structure comprising a pair of bifurcated pole tips each having its two legs positioned opposite like legs

of the other pole tip, means for maintaining said pole tips in definitely spaced relation, an armature having its ends positioned between adjacent ends of the two pole tips, means for supporting said armature for movement about a central transverse axis, and a coil operatively positioned relative to said armature, the ends of said armature being chamfered to lie in planes parallel to the planes of the ends of the adjacent pole tip legs at the limits of the armature's vibrations.

25. An electromagnetic structure comprising a pair of opposing pole tips, a coil positioned in operative relation thereto, an armature positioned between said pole tips, and an armature mounting including a member resisting movement of the armature and characterized by an increasing ratio of resistance towards the ends of the armature's movement from its normal position, said armature and the pole tips cooperating therewith being formed to increase the magnetic flux passing therebetween towards the ends of the armature's movement to compensate for the disproportionate increase in resistance of said mounting.

26. An electromagnetic structure comprising a pair of opposing pole tips, a coil positioned in operative relation thereto, an armature having an end positioned between said pole tips, and an armature mounting including a member interposing torsional force to the movement of said armature from its normal neutral position, the end of said armature being chamfered to approach parallelism with the adjacent ends of said pole tips towards the limits of its movement.

27. An armature mounting for an electromagnetic structure comprising a pair of spaced supports, a stud receivable in each support, a resilient strip extending between said studs, and an armature supported upon said strip.

28. An armature mounting for an electromagnetic structure comprising a resilient strip, means engaging the opposite ends of said strip for supporting and tensioning it, and an armature supported only from said strip.

29. An armature mounting for an electromagnetic structure comprising a resilient strip, means engaging the opposite ends of said strip for supporting and tensioning it, and an armature supported between its ends from said strip.

30. An armature for an electromagnetic structure comprising a plurality of laminations, an armature support engageable with the several laminations only between their ends, and means interengageable between the support and the laminations to maintain the latter fixed in relationship.

31. An armature for an electromagnetic structure comprising a plurality of lamination

- tions each having a shoulder substantially at its center, and a supporting strip engageable with said laminations and with the shoulders thereof to fix the several laminations in position relative to each other. 5
32. A magnetic structure comprising a magnet having its opposing poles disposed in spaced parallel planes, two pole tips therebetween, means rigidly maintaining 10 said pole tips in spaced relation, and means for drawing each magnet pole into intimate contact with its respective pole tip. 15
33. A magnetic structure comprising a magnet having its opposing poles disposed in spaced parallel planes, two pole tips each comprising a plurality of laminations disposed in planes normal to the planes of the magnet poles, and positioned therebetween, means for maintaining said pole tips in 20 definitely spaced relation, and means for drawing each magnet pole into intimate contact with each lamination of its respective pole tip. 25
34. A magnetic structure comprising a magnet having its opposing poles disposed in parallel overlapping relation, a magnet pole tip unit positioned between said magnet poles, and comprising two opposed pole tips and spacer means secured to each of said 30 pole tips to maintain a definite spaced relation therebetween, and means for clamping said pole tips between the overlapped poles, the spacer means being of less extent than the pole tips, in a direction normal to the planes of the magnet poles, whereby the 35 poles bear only upon the pole tips. 40
35. A magnetic structure comprising a magnet, a magnet pole tip unit comprising two opposed pole tips and spacer means secured to each of said pole tips to maintain a definite spaced relation therebetween, two pole pieces positioned to contact with the respectively opposite pole tips, a plurality of screws secured in each pole piece and 45 engaging the pole tip unit to retain it fixed in relation to the pole pieces and to clamp the unit therebetween, and a single screw passing through each of said pole pieces and received in the respective poles of the magnet to connect the pole pieces and pole tips thereto. 50
36. An electromagnetic structure comprising a pair of opposed pole tips, spacers at opposite sides of said pole tips, each spacer 55 being recessed intermediate its sides and ends, said spacers being secured directly to each pole tip to maintain the tips in definitely spaced relation, and to form therewith a housing, a coil located within said housing, and an armature disposed in operative relation to said coil and pole tips. 60
37. An armature mounting for an electromagnetic structure comprising a pair of spaced supports, a resilient strip extending 65 between said supports, two means supported each in one of said supports, and engaging the opposite ends of said strip to support it, an armature supported upon said strip, and means for adjusting the separation of said first pair of means to vary the tension in said strip. 70
38. An armature mounting for an electromagnetic structure comprising a pair of spaced supports, a resilient strip extending 75 between said supports, two means supported each in one of said supports, and engaging the opposite ends of said strip to support it, an armature supported upon said strip, and means for adjusting the two first means relative to each other to vary the relative angular position of the two ends of the strip. 80
39. An armature for an electromagnetic structure comprising a resilient strip adapted to be supported by both ends, and a plurality of laminations supportingly engaged 85 between their ends by the strip between its ends. 90
40. An armature for an electromagnetic structure comprising a plurality of laminations each having a shouldered lug substantially at its center, adjoining lugs having their shoulders oppositely faced and spaced slightly to form a channel extending transversely of the series of laminations, and means for maintaining said laminations 95 fixed in position comprising a transverse member received in said channel. 100
41. An armature for an electromagnetic structure comprising a plurality of laminations each having a shouldered lug substantially at its center, adjoining lugs having their shoulders oppositely faced and spaced slightly to form a channel extending transversely of the series of laminations, the transverse interstices between lugs being 105 filled with solder to unite the laminations and to complete the channel; and a transverse supporting member received in said channel. 110
42. An electromagnetic structure comprising a pair of opposed pole tips, non-magnetic spacers at opposite sides of said pole tips secured directly to each pole tip to maintain the tips in definitely spaced relation, a coil within the space between said pole tips 115 and said spaces, means in said space engaging said coil to maintain it fixed in position, and an armature disposed in operative relation to said coil and pole tips. 120
43. An electromagnetic structure comprising a pair of opposed pole tips, non-magnetic spacers at opposite sides of said pole tips secured directly to each pole tip to maintain the tips in definitely spaced relation, a pair of diametrically opposed shouldered studs, one received in each of said spacers, a pair of coils within the space between said pole tips and said spacers, one of the said coils being positioned at each side of a line connecting 125 said shouldered studs, and being held be- 130

tween the adjacent legs of both pole tips and the reduced portions of said two shouldered studs, and an armature disposed in operative relation to said coils and pole tips.

44. An armature for an electromagnetic structure comprising a resilient strip, means for tensioning said strip, and an armature body supported on said strip and projecting at opposite sides thereof.

45. An armature for an electromagnetic **10** structure comprising a resilient strip, means supportingly engaging the opposite ends of said strip, and an armature body secured on said strip intermediate its ends and projecting at opposite sides thereof.

Signed at Seattle, King County, Washington, this 13th day of February, 1925.

BERNARD A. ENGHOLM.
